**FLYING-OFF REEL WITH ROLLERS TRUING A
WIRE FED THERETO**
Franz Gerst, Schulstrasse 10, Ihmert,
Westphalia, Germany
Filed Aug. 24, 1962, Ser. No. 219,225
Claims priority, application Germany, Aug. 25, 1961,
G 33,013
5 Claims. (Cl. 72—183)

The present invention relates to a flying-off reel with rollers truing a wire fed thereto.

The setting up of a flying-off reel for the truing of rough wires, particularly of wires having a diameter of more than 18 mm. is difficult and requires much time and labor. In order to feed such heavy wire binding between the rollers, it is not only necessary to bend out the binding winding or wire ring, but to stretch the end of the wire bent in its heated state, so that it is gripped by the rollers. As a rule, this is accomplished by striking with heavy hammers, whereby, in order to avoid a damage of the reel and of the wire, an appreciable skill is required. These difficulties are particularly great and endanger the continuous operation in continuously discharging reels.

It is, therefore, one object of the present invention to provide a flying-off reel with rollers truing a wire fed thereto, which includes a mechanical wire-forcing device.

It is another object of the present invention to provide a flying-off reel with rollers truing a wire fed thereto, wherein the flying-off reel is formed such, that a gripping-member, the movement of which is controlled, is disposed in front of the rollers in the direction of feeding, and the mouth of which, which is disposed at first radially towards the wire ring and receives clampingly the end of the wire, is advanced by a swinging movement into the wire-forcing device.

The starting end of the wire of a wire binding is thus fed without any manual labor between the rollers, in accordance with this arrangement. This feeding takes place, thereby, on a predetermined moving path, which takes into consideration the most favorable conditions, whereby the feeding into the radially disposed mouth does not offer any difficulties. By such arrangement, mounting times are obtained, which are shorter for a multiple than could be obtained heretofore, so that a working of the reel without pause can be obtained.

It is still another object of the present invention to provide a flying-off reel with rollers truing a wire to be fed thereto, wherein a grab-member is rotatably mounted on a longitudinally movable slide and is formed with a leg, the movement of which is controlled by the marginal edge of an angular slot.

It is of advantage, thereby, and the catching of the end of the wire is simplified, if, in accordance with the present invention, the forcing-member or tappet is disposed, for clamping the end of the wire in the mouth thereof, cross-wise to the latter.

It is still a further object of the present invention to provide a flying-off reel with rollers truing a wire to be fed thereto, wherein the feeding of the end of the wire to the rollers is brought about in simplest manner by a wire slide guide rounded on its back side and disposed in front of the two rollers, which are disposed in superposed position, the wire slide guide having a tongue member directed towards the wedge formed between the rollers.

It is also still another object of the present invention to provide a flying-off reel with rollers truing a wire to be fed thereto, wherein a simplification of the clamping of the wire end into the mouth of the gripping-member is brought about by means of a mechanical cable line adapted for inserting the wire end into the mouth of the

gripping-member, which cable line is disposed on top of the gripping-member.

With these and other objects in view, which will be come apparent in the following detailed description, the present invention will be clearly understood in connection with the accompanying drawings, in which:

FIGURE 1 is a front perspective view of a flying-off reel designed in accordance with the present invention;

FIG. 2 discloses schematically in a front elevation of the flying-off reel the insertion of the wire end into the gripping-member;

FIG. 3 is a front elevation showing schematically, similar to the showing in FIG. 2, the controlled movement of the gripping-member, whereby the wire end is moved into a position in front of the rollers;

FIG. 4 is a schematic showing, similar to that in FIG. 3, wherein the wire end is in an advanced position between the rollers;

FIG. 5 is a similar elevation showing schematically the position of the wire upon return of the gripping-member into its original position;

FIG. 6 is a fragmentary view, showing at an enlarged scale a front elevation of the wire-slide guide;

FIG. 7 is a front elevation, shown at an enlarged scale, of the gripping-member; and

FIG. 8 is a section along the line 8—8 of FIG. 7.

Referring now to the drawings, and in particular to FIG. 1, the flying-off reel comprises a box-like stand 1 which carries at its front end a reel axle 2, on which the drum 3 is rotatably mounted. Preferably immovable supporting arms 4 are disposed at the front end of the drum 3, on which supporting arms 4 are mounted heavy wire rings and which are slipped on the drum 3 by mechanical or hydraulic operation. Adjustable slide pins 5 are additionally arranged for the support of the wire ring binding.

A guide blade disk 6 is disposed at the rear of the drum 3, and a set of rollers is mounted in a segment-shaped recess of the disk 6 for movement relative to each other on the stand 1, the set of rollers consisting of the driven roller 7, the settable counter roller 8 and a supporting roller 9 disposed in front of the driven roller 7.

The driven roller 7 and the counter roller 8 are equipped with grooves complementary to the profile of the wire. A wire slide guide 10, rounded off on its rear side, is disposed in front of the two rollers 7 and 8, the latter being in superposed position, which wire slide guide 10 has a tongue 10' (FIG. 6) directed into the wedge formed between the rollers 7 and 8.

A gripping-member 11, controlled for its movement in the direction of feeding, indicated by the arrow x in FIG. 2, is disposed in front of the rollers 7, 8 and 9. The gripping-member 11 has a mouth formation 12 (FIG. 8) and is also equipped with a tappet 13 disposed cross-wise to the mouth 12 for clamping the wire end.

The gripping-member 11 is rotatably mounted on a hollow shaft 14 in a longitudinally movable slide 15, which is mounted for linear movement along the back face of the front wall 1' of the box-like stand 1 in a guide plate 16.

The front wall 1' is equipped with a slot 17 through which the gripping-member 11 projects, the edge faces 17' and 17'' of the slot 17 extend angularly to the main portion of the slot 17. A leg 18, formed on the gripping-member 11, is disposed on the slot 17, which leg 18 is designed as a rectangular plate and the corners of which plate are fitted into the slot 17 as guide edges 18', 18'' and 18'''. The lower longitudinal edge 19 of the leg 18 is fitted as a sliding face for engagement with the slot edge 17'', while the control edges 18' and 18'', respectively, or 18''' engage during their travel at times the slot edges 17' and

17", respectively, and cause a swinging movement of the gripping-member 11 about the axis of the hollow shaft 14 about which the gripping-member 11 can turn. This swinging movement is arranged in such manner, that the mouth formation 12, which is at first disposed radially toward the wire ring 30 and which receives the end of the wire, is advanced during the swinging movement in the direction to the wire end, whereby the latter end is forced to swing such, that it is set on the wire slide guide 10 and is then inserted into the slot between the spaced-apart rollers 7 and 8.

A spindle 20, disposed parallel to the guide plate 16, serves as a drive for the corresponding movement drive of the slide 15, which spindle 20 may be driven mechanically and which brings about a linear reciprocating movement of the slide 15. The guide plate 16 is secured to the rear face of the front wall 1.

The clamping of the wire is brought about by the tappet 13 which is equipped with a forked head 27, arranged with fork ends projecting on both sides of the gripping-member 11 and each including a prismatic bearing 28. A cam 25, mounted for rotation with a rotatable shaft 26 and engaging the rear end of the tappet 13, causes the advancement of the tappet 13 for the purpose of clamping the wire. A helical spring 24, surrounding the tappet 13 within the hollow shaft 14, brings about the return movement of the tappet 13.

The roller 8 is mounted in an eccentric bearing 29, which can be displaced by means of a connecting rod 31.

In addition, a mechanical cable line 32 is provided on the stand 1, the cable 33 of which is equipped with a hook 34 for the purpose of attaching thereto the wire end of the wire ring 30.

The operation of the described apparatus is shown schematically in FIGS. 2-5.

FIG. 2 discloses the insertion of the wire end into the gripping-member 11 by means of the cable line 32, the gripping-member 11 being at this state in its original position, in which the mouth formation 12 of the gripping-member 11 disposed radially toward the wire ring 30 and the mouth formation opening is directed thereto. Upon pulling of the cable 33 to which the wire end has been hooked, the wire ring 30 is opened up and the overhanging portion of the wire is pulled into the mouth formation 12 of the gripping-member 11. Then, the wire 45 is clamped by the tappet 13 and the cable 33 with its hook is removed from the wire end.

The rollers 7 and 8 are then brought into their spaced apart position, and the slide 15 carrying the gripping-member 11 is moved in the direction of the arrow x. The angular slot 17 in the front wall 1' of the stand 1 controls the swinging of the gripping-member 11 by change in the support of the leg 18 of the gripping-member 11, as shown in FIG. 3, so that the wire end swings down and assumes a position in front of the spaced-apart rollers 7 and 8. The further movement of the gripping-member 11 causes the complete insertion of the wire end between the spaced-apart rollers 7 and 8, whereupon the latter are moved into engaging position (FIG. 4). The anvil-shaped wire slide guide 10, disposed between the angular space between the rollers 7 and 8, serves as support for the wire end, in order to provide already before the insertion of the wire end between the rollers 7 and 8 a support for said wire end. As soon as the discharging rollers 7 and 8 have gripped the wire end, the gripping-member 11 opens up by the return movement of the tappet 13. The wire leaves the mouth formation 12 of the gripping-member 11 and engages the forward roller 9, due to its bending tension.

The gripping-member 11 is then returned to its original position (FIG. 5) and the wire is continuously fed through the driven rollers 7 and 8 with simultaneous unbending of the wire ring, whereby the wire winding 30 is un-

wound, while the wire winding 30 engages the rotatable drum 3 and is supported by the slide pins 5.

The operation of the spindle 20, of the shaft 26 and of the connecting rod 31, as well as of the cable line 32, can take place mechanically, electrically or hydraulically and can be performed by any suitable conventional means.

While I have disclosed one embodiment of the present invention, it is to be understood that this embodiment is given by example only and not in a limiting sense, the scope of the present invention being determined by the objects and the claims.

I claim:

1. A flying-off reel with rollers truing a wire fed thereto from a wire ring, comprising a stand including a front wall, a drum secured to said front wall and adapted to support a wire ring, rollers having a profile complementary to the cross-section of wire to be trued and rotatably mounted on said front wall, a gripping-member disposed in front of said rollers and movement controlled during movement of said wire in the direction of removal, said gripping-member including means for clamping the free end of said wire to be trued and for advancing the free end of said wire, said clamping means comprising a mouth formation radially open toward said wire ring and clamping the free end of said wire, a slide secured to said front wall for linear movement parallel to said front wall, said gripping-member head being rotatably mounted on said movable slide, said front wall having a longitudinal slot with an angularly shaped end portion and defining marginal edges and receiving said gripping-member, means reciprocating in said mouth formation for gripping said wire, and means effecting said reciprocating motion.
2. The flying-off reel, as set forth in claim 1, wherein said gripping-member has a leg member movable along and controlled by said marginal edges of said angular slot.
3. The flying-off reel, as set forth in claim 1, wherein said means reciprocating in said mouth formation comprises a tappet disposed in said mouth formation of and crosswise to said gripping-member head.
4. The flying-off reel, as set forth in claim 1, wherein two of said rollers are disposed in superposed position, and which includes a wire slide guide rounded up at its rear and disposed in front of the lower of said superposed rollers, and said wire slide guide having a tongue projection extending into the space defined between said superposed rollers.
5. The flying-off reel, as set forth in claim 1, which includes a cable line disposed above said gripping-member and adapted to lift the end of said wire into the mouth formation of said gripping member.
